UNITED STATES PATENT OFFICE

2,469,477

STITCH SEPARATING MACHINE

William Selwyn Robson, Leicester, England, assignor to United Shoe Machinery Corporation, Flemington, N. J., a corporation of New Jersey

Application August 29, 1947, Serial No. 771,311
In Great Britain October 11, 1946

2 Claims. (Cl. 12—41)

1

This invention relates to shoe machines and is herein illustrated in its application to stitch separating machines of the type illustrated in United States Letters Patent No. 1,357,511, granted November 2, 1920, on an application filed in the name of Frederick H. Perry. It is to be understood, however, that the invention is not limited in scope to stitch separating machines but is equally applicable to other types of shoe machines and particularly to machines having heated work-engaging elements.

Stitch separating machines of the type herein illustrated and described operate upon the stitches in the outwardly extending margin of the sole portion of a shoe to indent the intervals between the portions of the stitches appearing on the upper surface of said extension.

The stitches in the extension of the sole portion of a shoe are usually treated with wax and, for this reason, it has been found desirable to apply heat to the stitch separating tool in order to soften the portions of the stitches engaged by said tool sufficiently to make them respond readily to its operation.

It is an object of the present invention to provide suitable means for conducting electricity to an electrical element mounted on the tool holder of a shoe machine. More particularly, it is the object of the invention to provide suitable means for heating the stitch separating tool of a machine of the type above referred to.

With the above objects in view, the invention in one aspect thereof consists in the combination with the elements of a shoe machine having a work engaging tool of an electrical element, such, for example, as a heating unit, mounted on the tool holder and means for conducting electricity to said electrical element, including a fine, flexible, non-resilient wire for conducting electricity to said element from a terminal on the carrier which mounts said holder, and a resilient conductor for conducting electricity from a fixed terminal on the machine frame to the terminal on said carrier. The fine wire flexes very readily and offers no appreciable resistance to free relative movement of the holder and the carrier incidental to the location of the tool relatively to the work. In the illustrated machine such relative movement is of such slight magnitude that said wire, although fine, will continue its slight

2

flexing action for a long time without breaking. The carrier is operated by power and consequently a resilient conductor which will withstand substantial flexing for a long period of time may be used to conduct electricity from the fixed terminal to the terminal on the carrier.

The invention will now be described with reference to the accompanying drawings and pointed out in the appended claims.

10 In the drawings,

Fig. 1 is a side elevation showing mechanism embodying the present invention incorporated in a machine of the type illustrated in the patent above referred to;

15 Fig. 2 is a side elevation similar to Fig. 1 illustrating said mechanism in greater detail and omitting the showing of the machine;

Fig. 3 is a side elevation illustrating certain details of construction;

20 Fig. 4 is a front elevation illustrating the tool holder and associated parts; and

Fig. 5 is an exploded perspective view illustrating the heating units in relation to a portion of the tool holder.

25 The illustrated machine is provided with an operating member or tool constructed and arranged to engage the upper face of the extension of the sole portion of a shoe supported upon a rotary table, and to exert a downward and inward pressure between adjacent outsole-attaching stitches thereby to separate the stitches and indent said extension widthwise thereof in order to give it a pleasing appearance.

The illustrative machine has a rotary work table 2 (Fig. 1), two presser feet of which one is shown at 4 in Fig. 1 and Fig. 3, and a tool holder 6 to which a stitch-separating tool 8 is secured. A rear end portion of the tool holder 6 carries a small upright pin 10 (Fig. 2) by means of which the tool holder 6 is pivotally mounted on an intermediate member 12. The member 12 is pivotally mounted on a short stud 14 secured to a carrier 16. The carrier 16 itself is mounted on a rock shaft 18 carried by two connected arms, 33 and 35, mounted on a shaft (not shown) journaled in the frame. The arrangement is such that, during the operation of the machine upon upstanding stitches visible upon the welt W of a welted shoe S, the arms 33 and 35 are operated to press the tool 8 downwardly between adjacent stitches of

the seam. During such pressure the member 12 swings slightly about the stud 14, against the action of a tension spring 24 connecting an upstanding ear 26 on the member 12 to an ear 28 on the carrier 16.

The tool 8 is reciprocated by the operation of the rock shaft 18 to feed the work step by step in a horizontal direction. For this purpose the carrier 16 has a depending ear 30 (Fig. 2) secured thereto which is actuated by a cam (not shown) whereby the carrier 16 is swung about the axis of the shaft 18 to cause the tool 8 to feed the work step by step from right to left across the front of the machine, return movement of the tool being effected by a spring (not shown).

In order to cause the tool 8 to be positioned between two adjacent stitches preparatory to the stitch-separating operation, the carrier 16, prior to each feed step, is given a small oscillatory motion in the direction of feed by a cam (not shown). In the course of this oscillation of the carrier the tool will enter the space between two adjacent stitches. In order that the tool will not be dislodged by the oscillation of the carrier after it has been correctly positioned relatively to the work the tool holder 6 is freely mounted on the pin 10 so as to permit the carrier 16 to oscillate without moving the tool holder. In order to maintain proper registration of the tool relatively to the work when the tool is out of work-engaging position, leaf springs 32 and 34 (Fig. 4) secured to the carrier 16 engage poppets 36 and 38 positioned at opposite sides of the holder 6 and mounted in the carrier, said springs being sufficiently weak to permit the tool to remain in its operating position on the work once it has been so located.

The construction and operation of the mechanism above described and of those portions of the machine not herein described are fully set forth in the patent hereinbefore referred to.

The tool 8 is heated by two parallel windings 40 and 42 of Nichrome wire (Fig. 5), the total resistance of each winding being about 10 ohms. Each winding is wound upon an insulating strip 44 and enclosed in an envelope of mica 46. The windings 40 and 42 are secured to opposite sides of a central portion of the holder 6, which is wrapped with mica 50, by screws 54 extending through cover plates 52. One end of each of the windings 40 and 42 is grounded to the holder 6 and the other end of each winding is connected to a nickel wire 56 which is very fine and flexible but substantially non-resilient. The wires 56, 56 are encased in an asbestos sleeve 58 and pass up over the carrier 16 (Fig. 4) to an insulated terminal 60 (Fig. 3), hereinafter referred to as the first terminal, mounted on a terminal block 62 on the opposite side of the carrier. Alongside the terminal 60 there is mounted on the block 62 a terminal 64 which is not insulated from the carrier 16 but is grounded thereto.

From each of the terminals 60, 64 a conductor, which is preferably a phosphor bronze strip 66, 68, extends upwardly and curves over the top of the carrier 16 (Fig. 4) and then down to a terminal block 70, 72 on a plate 73 secured to the machine frame 22 (Fig. 1). The terminal block 70, hereinafter referred to as the second terminal, to which the strip 66 is secured, is insulated from the plate 73 and the terminal block 72 is grounded

to said plate. The terminal blocks 70, 72 are connected to a suitable source of electricity. A suitable sheet metal guard may be provided to enclose the strips 66, 68. When the current is turned on, the tool 8 is heated by about 100 watts, which has been found to be adequate for the purpose in view.

With the arrangement described the fine, flexible nickel wires 56, 56 do not substantially restrict relative movement of the tool 8 and the carrier 16 when such movement is required in the operation of the machine, but such relative movement is small and does not impose much continued flexing on the wires 56, 56. Early failure 15 of the latter due to wear is thereby avoided. On the other hand the strips 66, 68 which are of a character more readily able to withstand continued flexing, but which, if joined to the tool holder 6 directly, would substantially impede relative movement of the tool holder and the carrier are joined to the carrier which is driven by the power of the machine and the movement of which is not readily restricted by such strips.

In the illustrative machine electrical means is 25 also provided for heating the work table 2 which means consists of a resistance bobbin mounted in a support 74 for the work table and dissipating about 20 watts. This small amount of power is adequate to heat the table 2 sufficiently to prevent undue accumulation of wax thereon.

Having thus described my invention, what I claim as new and desire to secure by Letters Patent of the United States is:

1. In a shoe machine, the combination with a 35 member constructed and arranged to operate on the upper surface of the extension of the sole portion of a shoe, a holder in which said member is mounted, a carrier, means connecting the holder to the carrier constructed and arranged to permit free relative movement of said parts and means mounting the carrier for work feeding movement, of an electrical element mounted on the holder, said element having a first end grounded, a first terminal mounted on the carrier, a second terminal secured in a fixed position, a fine, flexible, non-resilient wire for conducting electricity from said first terminal to a second end of said electrical element, and a resilient conductor for conducting electricity from 45 said second terminal to said first terminal.

2. In a shoe machine, the combination with a 50 stitch separating tool, a holder in which said tool is mounted, a carrier, means mounting the holder on the carrier constructed and arranged to permit free relative movement of the carrier and the holder about a first axis, and means mounting the carrier for movement about a second axis, of an 55 electrical heating unit mounted on said holder, said unit having a first end grounded, a first terminal mounted on the carrier, a second terminal secured in a fixed position, a fine, flexible, non-resilient wire constructed and arranged to conduct electricity from said first terminal to a second end of said heating unit, and a relatively 60 heavy resilient conductor constructed and arranged to conduct electricity from said second terminal to said first terminal.

WILLIAM SELWYN ROBSON.
